UNITED STATES PATENT OFFICE.

CHARLES LEISIFER, OF ALLEGHENY, PENNSYLVANIA.

MITERING-MACHINE.

SPECIFICATION forming part of Letters Patent No. 645,106, dated March 13, 1900.

Application filed January 17, 1898. Serial No. 702,414. (No model.)

To all whom it may concern:

Be it known that I, CHARLES LEISIFER, a citizen of the United States of America, residing at Allegheny, in the county of Allegheny and State of Pennsylvania, have invented certain new and useful Improvements in Miter-Machines, of which the following is a specification, reference being had therein to the accompanying drawings.

10 My invention relates to certain new and useful improvements in mitering-machines.

One object of my invention is to provide a simple and effective mitering machine or box adapted for all possible use for the cutting of 15 any angle.

A further object of my invention is to construct a mitering-machine of this character which is provided with means for securing in position a pair of standards or saw-guides to 20 allow of the cutting of the proper angle.

A further object of my invention is to construct a mitering-machine of this character for cutting all possible angles and for locking the saw-guides automatically in the desired position.

25 A further object of my invention is to adapt the brace for the saw-frame for keeping the saw while cutting any angle in the desired position.

30 A further object of my invention is to provide, in connection with the mitering-machine, an adjustable saw-blade.

A further object of my invention is to provide means for regulating the depth of the 35 cut desired.

My invention finally consists in the novel combination and arrangement of parts hereinafter more fully described, and particularly pointed out in the claim.

40 In describing the invention in detail reference is had to the accompanying drawings, forming a part of this specification, wherein like numerals of reference indicate corresponding parts throughout the several views 45 thereof, and in which—

Figure 1 is a perspective view of my improved mitering-machine. Fig. 2 is a vertical sectional view of the operating-handle carrying the automatic stop for the guide-pins or 50 standards. Fig. 3 is a side view of a portion of my improved adjustable saw. Fig. 4 is a cross-sectional view of my improved machine.

Fig. 5 is a vertical sectional view of one of the guide-pins or standards, showing a stop arranged therein for regulating the depth of the 55 cut. Fig. 6 is a perspective view of the pin for locking the guide-pins or standards in the desired position. Fig. 7 is a top plan view of the operating-handle for the guide-pins or standards.

60 Referring to the drawings by reference-numerals, 1 indicates a box for holding the molding plank or board 1', that is provided with legs or supports 2 and a pair of sides (only one shown) which are divided into sections 3 4. These sections are suitably spaced apart to allow of the operation therethrough, or, in other words, for the cutting of the miter by the saw 5.

The supports or legs 2 elevate the table or 70 box 1, so as to allow of the operation under the same and under the segment-shaped rack-bar 6 of the operating-handle 7. The segment-shaped bar 6 acts as a stop for the operating-handle, and consists of a flat piece of 75 metal having a series of notches 8 arranged on the outer edge thereof. These notches are adapted to receive the stop-pin 9, which is substantially L-shaped and operates through an L-shaped recess 10, formed in the support 80 or operating-handle 7. The lower portion of the recess is closed by means of a metal plate 11, which is secured to the lower face of the support or operating-handle 7 by means of 85 the screws 12. The lower portion of the stop-pin 9 is formed with a downwardly-extending projection 13, forming a finger-catch, to allow of its operation. This downwardly-extending projection operates through an elongated slot 14, formed in the plate 11. The 90 pin 9 is held in position in the notches 8, formed on the rack-bar, by means of a coil or tension spring 15 operating against the same. This spring is arranged in the lower portion of the recess 10. (For illustration 95 see Fig. 2 of the drawings.) The insertion of this spring in the recess and the abutting of the same against the pin 9 makes the pin spring-actuated.

The support or operating-handle 7 is provided with a smaller extension 7' to allow of 100 an easy gripping of the same at its operation. This support or operating-handle 7 is formed of an oblong strip of suitable material, which

is pivotally secured to the box 1 by means of the bolt 16 and nut 17 and extends outwardly on both sides of the box 1. (For illustration see Fig. 4 of the drawings.)

5 Secured to the upper face of the support or operating-handle 7 are the upwardly-extending saw-guides 18. These saw-guides have an elongated slot 19 formed through a portion thereof, as shown, to allow of the operation 10 of the saw-blade 5 therethrough. These saw-guides are of cylindrical shape and hollow, as shown, and are adapted to receive the stop-rods 20 for regulating the depth of the cut. These stop-rods are also hollow and have the 15 periphery thereof screw-threaded, which meshes with the screw-threads formed on the inner face of the saw-guides.

21 and 22 indicate the sides of the saw-frame, the side 22 having formed integral 20 therewith the handle 23, and these sides are bifurcated at the lower ends, in which is secured the saw-blade 5 by means of the set-screws 24.

25 denotes a strengthening rod or brace secured to the upper end of the sides 21 22, and 26 indicates an additional brace suitably secured to the sides 21 22 at about the center thereof. The lower face of this brace or rod 26 is provided with an elongated groove 27, 30 which is adapted to receive the upper end of the stop-rods 20 when the saw has cut the miter sufficiently deep. Furthermore, until the further cutting of the miter has been arrested by the top of the groove 27 being brought 35 into contact with the ends of the stop-rods 20 the sides of the groove will prevent the wobbling or sagging to one side when the stop-rods enter the groove.

In Fig. 3 of the drawings I show a saw-blade having a series of apertures 28 for adjusting the saw—that is, to regulate the depth of the cut. This construction can be readily understood without further description thereof.

45 It will be readily apparent that by pulling the pin 9, by means of the downwardly-extending projection 13, toward the operator the same will be released from the notches in the stop-bar 6, and owing to the handle 7 being 50 pivotally secured to the box 1 the same can be moved in the direction desired to obtain the preferred angle, and on the release of the downwardly-extending lug 13 the spring 15 will force the pivot-pin 9 into the preferable 55 notch and secure the handle 7 in the desired

position. Owing to the saw-guides being secured to the upper face of the handle, the proper angle can be readily obtained when the miter is being cut by the saw-blade.

The depth of the cut may be regulated by 60 the adjustable saw-blade and also by the stop-bar 20, as when the upper ends of these bars come in contact with the brace 26 further cutting of the miter will be arrested thereby, and this will also serve to protect the box or table 65 1 from being injured by the saw.

It will be noted that various changes may be made in the details of construction without departing from the general spirit of my invention.

Having thus fully described my invention, what I claim as new, and desire to secure by Letters Patent, is—

In a mitering-machine, the combination of a table or box adapted to receive the material to be cut, an operating-handle pivotally connected to the underneath face thereof and provided with an L-shaped opening in one end thereof, a pair of vertically-extending hollow saw-guides provided with interior 80 screw-threads, one of the said guides mounted near each end of the said handle and each provided at their lower end with an elongated slot, a saw-frame, an adjustable saw-blade secured to the said frame and operating 85 through the said slots, a pair of screw-threaded stop-rods engaging in the said guides, a brace 26 carried by the said saw-frame provided in its underneath face with an elongated groove in which operate the said stop-rods for limiting the downward movement of the said saw-frame, an L-shaped stop-pin mounted in the L-shaped opening of the said handle, a plate secured to the underneath face of the said handle for supporting the L-shaped stop-pin, a spring mounted on the said plate and operating against the said pin for retaining the same in a locked position, a finger-catch formed integral with the said pin, and a segmental rack-bar secured to the said table or 100 box and provided on its outer edge with a series of notches adapted to be engaged by the said stop-pin, substantially as described.

In testimony whereof I affix my signature in the presence of two witnesses.

CHAS. LEISIFER.
